UNITED STATES PATENT OFFICE.

CLARENCE LIPPER, OF PHILADELPHIA, PENNSYLVANIA.

HAT.

Application filed September 3, 1925. Serial No. 54,359.

This invention relates to hats, and a process or method of making them.

The present invention comprehends a new and distinctive type of hat, preferably 5 a lady's hat, which is of narrow fabric in various designs, the design being regulated by the formation of the narrow fabrics during their braiding into the hat form and it also embodies the process or method of 10 making the hat whereby a hat may be made in a relatively short space of time, with extreme accuracy, minimum amount of manual labor, and at a relatively very low cost.

The process of making hats, as embodied 15 in the present invention, consists essentially of mechanically braiding a plurality of ends of narrow fabric, by means of a braiding machine in a tubular hat body, by braiding the narrow fabric over a suitable 20 form and gradually varying the elevation of the form as the braiding proceeds to provide the desired shape to the hat, tying the ends of the narrow fabric at the top or crown of the hat and arranging them in 25 such manner as to provide a neat closure at the crown, the tying of the ends of the fabric at a point beyond the normal brim of the hat and trimming on inside of the body of the hat and fastening them in any 30 suitable manner so as to provide rounded neat appearing, comfortable rim in the hat.

Other objects of the invention will appear in the following detail description, and in the accompanying drawings wherein:

Figure 1—is a view showing a completed hat constructed in accordance with this invention.

Figure 2—is a detail section through a 40 completed hat.

Figure 3—is an elevation of a hat showing one of the stages in the forming or making of the hat.

Figure 4—is a detail view.

Referring more particularly to the drawings, the body 1 of the hat is formed of a plurality of lengths of narrow fabric, and in constructing the hat, the lengths of narrow fabric are braided over the fabric frame 50 2 which may be made of buckram or any other suitable material. An adhesive 3 of any approved type, is first placed over a buckram frame 2, and after the body is braided over the form, the hat is ironed or 55 pressed by a hot iron, to cause adhesion of the braided body 1 to the frame 2. A lining

4 of approved type, is placed within the hat to finish it; while in the drawings, only one design of braiding is illustrated, it is to be understood that an unlimited number of 60 designs may be made without departing from the spirit of this invention, and by merely regulating the cam action of the machine on which the body is braided.

Specifically, the process of making the hat 65 comprises the use of a machine commercially known as a braiding machine, in the textile industry, and the braid to be used in making the hat is placed on the bobbins (not shown) in the usual manner, and a block shaped to 70 conform to the shape of the hat, to be braided, is used in the center of the machine. The ends of the fabric from the bobbins are drawn to the center and are tied after which the machine is started and during the braiding operation, the form is gradually elevated, resulting in the braiding of a tubular mesh or braiding which comprises the body 75 of the hat. The use of the form about which the narrow fabrics are braided, regulates the 80 specific shape of the resulting hat body and when the body is woven over the buckram frame, the buckram frame is placed upon the form on the machine and is coated with the adhesive 3 before the braiding starts. A 85 few rows of braiding are made beyond the lower edge of what is to be the hat brim, and at the end of these last rows, the ends of the narrow fabric are tied, and are then cut free from the bobbins, leaving a form 90 such as shown in Fig. 3 of the drawings. That is, a cluster of knotted ends at the crown of the hat, together with a cluster of knotted ends, at circumferentially spaced points about the rim of the hat. After the 95 ends are tied and cut loose from the fabric on the bobbins, the knotted ends at the crown of the hat are drawn inwardly into the hat and flattened against the inner surface of the crown. In cases where the buckram frame is used, this frame is cut at the top or center of the crown and the knotted ends are drawn through the opening thus formed, and are flattened against the inner surface of the buckram frame. If it is so 100 desired, they may be stitched or otherwise suitably fastened. The rows of braiding which have extended beyond the normal rim of the hat, are then doubled back into the hat, as shown at 6, in Figure 2 of the drawings and they are stitched or otherwise suitably attached to maintain them in position.

The hat is then placed on a suitable hat block shaped to conform to the shape of the hat, and is pressed by a hot iron or other suitable heated pressing member to apply 5 both pressure and heat to the hat, and cause the adhesion of the braided body to the buckram frame,—in cases where a buckram frame is used. Where the buckram frame is not used, the hat is lined without its being 10 applied to the block and pressed. Where the buckram frame is used and the hat is placed on a suitable pressing block it is after having been pressed, removed from the block, and the lining 4 placed therein in the 15 usual manner of putting linings in a hat and the hat may then be trimmed—if desired, in any approved manner.

Summing up generically, the process of forming the hat constructions in mechanically braiding a plurality of lengths of narrow fabric about a form, or about a form and flexible frame, to provide a braided tubular body, the ends of the fabric being properly tied and inserted into the body 25 of the hat to complete the neat, attractive appearance, after which the hat is lined.

It will be readily understood that numerous different designs and color effects may be had in the braiding of the hats.

30 It is of course, to be understood, that the invention may be constructed in various other manners, and the parts associated in different relations, and therefore, I do not desire to be limited in any manner, except 35 as set forth in the claims hereunto appended.

What I claim is:—

1. The process of making a lady's hat which comprises applying an adhesive coat-

ing on a stiffening hat frame while the latter fits a hat form, interlacing or braiding narrow fabric over the adhesive coating, applying pressure and heat simultaneously causing a binding of the fabric to the stiffening hat frame, tying the ends of the narrow fabric at circumferential spaced intervals about the rim, tucking said tied ends inwardly and securing them to the inner face of the rim, knotting together all of the ends of the narrow fabric at the crown of the hat and drawing them inwardly through the stiffening hat frame and mashing them against its inner face, and then applying an inner lining adjacent the inner face of the stiffening hat frame. 40 45 50 55

2. In a hat, the combination with a stiffening hat frame, of a fabric braiding and a coating of adhesive on the hat frame to secure the braiding to the frame, the crown of the hat frame having a centre opening, 60 said braiding consisting of narrow lengths of fabric braided together, with certain of their ends extending through the opening in the hat frame and bent and flattened back against the inner surface of the frame to 65 close the opening, means tying said ends, the lower bottom edge of said braiding turned inwardly and upwardly at the bottom edge of the hat frame and against the inner surface thereof, the lower portions of the said narrow lengths of fabric having their ends tied together at circumferentially spaced intervals about the rim, and secured to the inner face of the hat frame; and an inner lining adjacent the inner facing of the stiffening hat frame covering the tied ends. 70 75

In testimony whereof I affix my signature.
CLARENCE LIPPER.
